GOVERNOR MECHANISM

William J. Williams, Wilmette, Ill.

Application November 27, 1944, Serial No. 565,383

1 Claim. (Cl. 264—3)

1

This invention relates to a governor mechanism constructed so that the resultant action produces a substantially straight line curve throughout the operating speed range of the governor, hence with a given change in speed of rotation of an element connected with the mechanism which is to be regulated, a corresponding substantially equal variation in movement occurs in a controlling element which may be connected to thereby regulate the movement of the basic mechanism of my improved type of governor.

An object of the present invention therefore is to provide in a governor mechanism having a controlling element, inertia means adapted for variable movement caused by the operation of centrifugal force and means arranged for modifying the movement of said inertia means in such a manner that said means may be connected with the controlling element and will move the latter in substantially the exact ratio of any variations in speed of a member connected with or driven from the mechanism to be governed.

Other objects include the simplification of parts; the compact arrangement of the elements; and in certain embodiments of my invention, of means to adjust the element actuated by the governor mechanism to vary the range of effective operative movement of the actuated element or the time of operation of the mechanism being controlled, or the like, a still further object being the simplified manner in which this adjustment may be accomplished.

Further objects and advantages are within the scope of this invention such as relate to the arrangement, operation, and function of the related elements of the structure, to various details of construction and to combinations of parts, elements per se, and to economies of manufacture and numerous other features as will be apparent from a consideration of the specification and drawings of a form of the invention, which may be preferred, in which:

Figure I is a vertical, sectional, elevational view of one embodiment of my invention shown connected with a throttle or other control linkage;

Figure II is a similar view taken at right angles to Figure I;

Figure III is a sectional plan view taken on the line III—III of Figure I;

Figure IV is a vertical, sectional view taken on the line IV—IV of Figure I;

Figure V is an external elevational view of a modification of my invention applied as a switch

2

operating governor to make and break circuits at set speeds;

Figure VI is a vertical sectional view of the embodiment of Figure V with the parts at rest;

5 And Figure VII is a similar view showing the parts in position to actuate a switch or other mechanisms;

Figure VIII is a diagrammatic view showing the operation while Figure IX is a diagram showing 10 the correlation of speed variation of the mechanism to be controlled compared with the movement of the control element of the governor;

Referring to Figure I, I have shown a governor housing 10 made in two parts as illustrated, having 15 an upper part 11, which, in certain embodiments of my invention may be adjustable with respect to the bottom part 10 as will hereinafter be pointed out. Within this housing 10 extends the drive shaft 12, the revolutions of which may 20 vary as being connected with some mechanism whose speed varies, the control of which it is the object of my governing mechanism to effect. The shaft 12 is mounted in a suitable bearing 13, the shaft 12 carrying within the housing, the 25 rotatable support 14 for the governor weights 15, the support 14 being pinned to the shaft 12 in the illustration. These governor weights 15 are pivoted as at point P to the support 14 so that under the centrifugal action of the revolving of 30 shaft 12 these weights move outwardly and downwardly around the point P as a center.

A freely movable sliding plunger or controlling element 18 is provided with collars 19 and 19', while the weights 15 have a contact tongue or 35 cam 20 fitting between collars 19 and 19' and adapted to move the plunger 18 longitudinally in line with the axis of the shaft 12 as cam 20 of the weights moves upwardly and downwardly as shown. It is to be noted that the weights 15 are 40 recessed at 21 to receive the collar 19.

Each weight 15 is connected to the control plunger 18 by a pair of springs 25, one end of each spring 25 being connected at point S to the slide or control plunger 18 and the other end connected 45 at the point W with the weight 15, the springs being normally under tension to retain the parts in the position illustrated in full lines in Figure I when the governor is at rest.

In the embodiment of Figures I to IV, the 50 controlling element or plunger 18 is connected by a suitable anti-friction thrust bearing 30 to a stem 31 extending through the housing 11 connected to a bell crank 32 pivoted at 33 to the top of the housing as shown. The bell crank 32 is intended to be connected with a throttle con-

trol link 34 for controlling the speed of any type of steam, internal combustion, or other engine or mechanism. The bell crank 32 may also be connected with a suitable member such as the member 34 for controlling the speed of a dynamo electric machine interposing resistances, etcetera, as may be desired.

As shown in Figure VIII, weight 15 moves outwardly around the point P as a pivot as the speed of the shaft 12 increases with the result that the cam 20 moves the collar 19 and the control plunger 18 tangentially in a vertical direction, assuming the governor to be located upright, as illustrated in Figure I. The spring 25, which has a modifying influence on the action of the weights 15 being connected at one point S to the sliding control plunger 18, assumes various positions affecting the cycle of the movement of the weights 15, and hence the anchor of the controlling spring 25 is not fixed in relation to the point W where the other end of spring 25 is connected to the weight 15. It will be noted that the point W and point S may be so chosen that the spring 25 is inclined to the horizontal when the parts are at rest as in Figure VIII and that upon outward movement of the weights 15 due to the action of centrifugal force, the point W moves by increments equal to the co-tangent of the angle of the line PW with the vertical through the point P. In the meantime, it will be seen that the contact point C of the cam 20 has moved the collar 19 and control plunger 18 by increments of equal amounts as illustrated in Figure III, upon various angular movements of the point C around the pivot point P. Thus, the several positions taken by the point S of the spring 25 vary substantially exactly in proportion to the several positions of the point C of the cam 20. By the arrangement disclosed, I have provided a mechanism which remains at initial position until after a certain increase in speed of the shaft 12 to a point where the centrifugal force will cause the weights 15 to move outwardly, and from then on I am able to provide a substantially straight line governor control of the movement of the control plunger 18, in exact proportion to the increase or decrease in the speed of rotation of the shaft 12. This is illustrated in Figure IX, where the base line 60 represents the speed of rotation of the shaft 12, and the vertical line 61 represents the movement of the control plunger 18. Plotting the R. P. M. of shaft 12 against the movement of the plunger, I have found I have obtained a straight line 62 over a large range of R. P. M. for the shaft 12, and irrespective of the strength of the springs 25 employed.

By the arrangement disclosed, it will be seen that I vary the angularity of the spring 25 on the weights 15; I vary the length of the springs and hence the effect of the modifying forces thereof acting with or against the effect of the weights 15 in the cycle of their movement in effecting governor control.

After an initial period, and the governor begins operating at low speed, the weight retarding springs tend to give an upward force on the plunger due to the placing of the pin in the plunger and the subsequent angularity. As the weights open slightly, due to increased speed and centrifugal force, the plunger will rise to the point where the springs are exerting a directly opposed force without any upward or downward component. As the speed is still further increased, the weights move farther out, and the plunger rises to the point where the plunger pin

is above the center of the pins in the weights. In this latter position, a downward force is exerted on the plunger to retard its movement, due to the angularity of the position of the springs. This construction results in a practically straight line curve throughout the operating range of the governor.

In the embodiment of my invention, illustrated in Figures V, VI, and VII, I have shown the application of my improved governor mechanism as an overspeed governor for controlling electric circuits in any desired system. In this case, the shaft 12 connected to be driven by any suitable connection with the electrical or other mechanism to be controlled is arranged in a bearing 13 in the housing 10 as in the other embodiment. Moreover, the corresponding parts described in the embodiment of Figures I through IV are the same in this embodiment of Figures V through VII, the main difference being that the controlling element or plunger 18 in the latter embodiment merely contacts the pin 40 of an electric control switch 41, mounted on the top of the adjustable part of the housing 11. It will thus be seen that when the plunger 18 reaches its upper position for any particular setting of the adjustable top portion 11 relative to the base 10 of the housing of the governor such as illustrated in Figure VII, the same operates the switch 41 by contact with the element 40 to break or make the circuit as stated.

Figure V illustrates an embodiment of my two-part housing 10 and 11, in which the lower part 10 has an indicating index 59 vertically arranged so that as the upper part is screwed upwardly and downwardly by reason of the screw threaded connection 51 illustrated in this embodiment, the pin 40 is moved away from and toward the plunger 18. In view of the fact that in the mechanism I have constructed, the governor provides a straight line control, it will be seen that I can provide equal variations in space of the indicia 55 on the rotating top 11, which can be readily adjusted to change the time of action of the switch or other mechanism provided.

The operation of the governor mechanism, itself, in the embodiment of Figures V to VII, is, of course, substantially the same as that described in the operation of the mechanism in connection with Figures I to IV.

It is apparent that, within the scope of the invention, modifications and different arrangements may be made other than is herein disclosed, and the present disclosure is illustrative merely, the invention comprehending all variations thereof.

What I claim is:

60 A governor mechanism including a governor housing; a vertically arranged rotatable shaft extending into said housing; a rotatable member carried by said shaft forming a rotatable support; a plurality of weights pivotally connected at their lower portions to said support and arranged to rotate with said member, said weights adapted to move in an arc around said pivots under the action of centrifugal force; a controlling member adapted to be vertically moved 65 in one direction by said weights; and a tension spring connected to each of said weights and to said movable controlling member one end of the spring being connected to the weight and the other end connected to said controlling 70 member at a point below the horizontal plane

passing through the connecting point of said spring to said weight in inoperative position, whereby the spring acts in conjunction with the weights on said controlling member during part of the movement of said weights and against said weights during other parts of such movement.
